Primary Examiner — Eric Goodman*Assistant Examiner* — Sloan Rozin(74) *Attorney, Agent, or Firm* — Banner & Witcoff, Ltd.(57) **CLAIM**

The ornamental design for a display screen with icon, as shown and described.

DESCRIPTION

The sole FIGURE is a front view of a display screen with icon showing the new design.

The broken line showing of the remainder of the user interface and the remainder of the display screen is for environmental purposes only and forms no part of the claimed design.

1 Claim, 1 Drawing Sheet(56)
